(21) Appl. No.: **29/087,115**

The ornamental design for a sending head for a handheld wireless transmitter, as shown and described.

(22) Filed: **Apr. 27, 1998**

DESCRIPTION

(30) **Foreign Application Priority Data**

Oct. 27, 1997 (DE) M97 09 906
FIG. 1 is a front elevational view of a sending head for a handheld wireless transmitter of the present invention;
FIG. 2 is a side view thereof, the other side being a mirror image;

(51) **LOC (7) Cl.** **14-03**

FIG. 3 is a top view thereof; and,

(52) **U.S. Cl.** **D14/155**; D10/104

FIG. 4 is a bottom view thereof.

(58) **Field of Search** D10/104, 106,

The rear view of the sending head for a hand held wireless transmitter forms no part of the claimed design.
